UNITED STATES PATENT OFFICE.

ISAAC D. SMEAD, OF TOLEDO, OHIO.

STAND FOR BICYCLES.

SPECIFICATION forming part of Letters Patent No. 495,210, dated April 11, 1893.

Application filed August 22, 1892. Serial No. 443,707. (No model.)

To all whom it may concern:

Be it known that I, ISAAC D. SMEAD, a citizen of the United States, residing at Toledo, in the county of Lucas and State of Ohio, have 5 invented certain new and useful Improvements in Stands or Supports for Bicycles, of which the following is a specification.

My invention relates to stands or supports for bicycles, and consists in a novel construction of the same as hereinafter set forth and claimed.

In the accompanying drawings,—Figure 1 is a perspective view of my improved stand or support as it appears when in use; Fig. 2, 15 a front face view of the same; Fig. 3, a horizontal sectional view on the line 3—3 of Fig. 2; and Fig. 4, a horizontal sectional view on the line 4—4 of Fig. 2.

The stand or support comprises an upright 20 post A having a foot piece B, which latter is adapted to be set into the ground as indicated in Fig. 1, so as to maintain the post in an upright position. The post portion comprises the vertical bars a, which are connected at 25 their lower ends by a horizontal crossbar b, and at their upper ends by a cross-bar or cap c, as shown in Figs. 1 and 2. The bars a are provided on their inner or opposing faces with vertical webs, ribs or flanges d, which extend 30 from the base plate or crossbar b about half-way up the bars a. Above this point the bars a are brought closer together and are provided with strengthening ribs or flanges e, as shown in Figs. 2 and 3, which flanges extend upward 35 from the point where the bars curve inward toward each other, to the top plate or cap c. Upon reference to Fig. 2 it will be observed that this construction results in the formation of vertical openings of different widths in the 40 post or standard, the upper slot or opening f being narrower than the lower slot or opening g.

Secured upon the upper face of the lower crossbar or base plate b in line with the center of the vertical slots f, g, is a socket piece 45 or curved seat h in which the wheel is to be rolled, and by which the lower edge of the wheel is supported, as clearly shown in Fig. 1. The upper edge of the wheel passes in the 50 narrow slot f and is embraced by the upright bars a which prevent the wheel from tipping or falling over sidewise. The flanges d pro-

jecting inwardly from the lower portions of the bars a, are so spaced as to prevent the wheel hub or axle from passing too far through 55 the post or support.

In the drawings I have shown the stand or support as composed of a single casting, but this is not essential, and I do not intend to restrict myself to the use of a post, stand or support made of a single piece of material, whether of wood or of metal, as it is obvious that it can be made up of sections and bolted or otherwise fastened together.

It will be observed upon reference to the 65 drawings that I have shown the post, stand or support as adapted to receive two wheels, but it is to be understood that the number of slots or openings f g may be increased or diminished as desired, without departing in any 70 way from the spirit of my invention. It will be found, however, in practice that two sets of such slots or openings will ordinarily be sufficient for general uses.

The post, stand or support may be ornate- 75 mented as desired or as the fancy of the manufacturer may dictate.

From the foregoing description it will be understood that this support is designed primarily to be used out of doors, it being fixed 80 permanently in place by setting its base B firmly in the ground at any convenient point. It is however obvious that it may be used indoors equally well, by simply omitting the base B and in lieu thereof providing it with lateral flanges by which it can be fastened to the 85 floor by means of screws; or with lateral arms or projections of sufficient length to enable it to stand without being screwed fast, if desired, these modifications being readily made 90 by any one skilled in the art, and therefore not necessary to illustrate.

Having thus described my invention, what I claim is—

1. A bicycle support consisting of an upright 95 or post A provided with one or more slots for the reception of the bicycle wheel, the upper portion of said slot being adapted to receive the rim of the wheel, and its lower portion of greater width to receive the hub, and having 100 inwardly projecting flanges to serve as stops and prevent the wheel from passing through the slot, substantially as shown and described.
2. In a bicycle support the combination of

an upright or post provided with one or more slots of varying width adapted to receive the rim and hub of the wheel, and a curved shoe or seat at the bottom of the slot for the wheel 5 to rest in, substantially as shown and described.

3. The combination in a bicycle support, of an upright or post provided with one or more slots of varying width to receive the rim and 10 hub of the wheel, a curved shoe or seat at the

bottom of the slot for the wheel to rest upon, and a base B adapted to be inserted in the ground, substantially as shown and described.

In witness whereof I hereunto set my hand in the presence of two witnesses.

ISAAC D. SMEAD.
